ULTRA HIGH FREQUENCY DEFLECTION
MODULATED TUBE

Edward J. Hefele, Bronx, N. Y., assignor to Bruno Patents, Inc., Long Island City, N. Y., a corporation of New York

Application May 16, 1945, Serial No. 594,086

4 Claims. (Cl. 315—3)

1

This invention relates to means for generating, multiplying or amplifying ultra-high frequency signals and at the same time providing means for radiating into space as electro-magnetic waves the signals so generated, amplified or multiplied.

Since the advent of ultra short or microwaves into radio and radar technique, it has been found that conventional vacuum tubes are not a satisfactory means for generating or amplifying such short wave or high frequency signals. In the present day microwave techniques, frequencies of the order of ten billion cycles per second are common. This means that an electrical impulse reverses itself completely in one ten billionth of a second. This extremely short interval of time is a good deal smaller than the time required for the flight of an electron from the cathode to the anode of a vacuum tube.

In the use of vacuum tubes at conventional radio frequencies, the time of flight of the electron, called the transit time, is always much smaller than the time required for the electrical impulse to reverse, i. e., which latter time is simply the numerical reciprocal of the frequency. Since this relationship is no longer true in the microwave technique, effects called transit time effects come into play which render nearly inoperative the ordinary vacuum tube. As a result of this failure, new types of tubes are applied in this domain. Such new types are the magnetron and Klystron. In both these latter types of tubes, a scheme of modulation known as velocity modulation is used. This is in contradistinction to the density modulation used in the ordinary vacuum tube.

In the conventional tube there is interposed between cathode and the anode one or more open mesh structures known as grids. When signal voltages are applied upon the first grid, these voltages influence the density of the electron beam proceeding from the cathode, and hence control the beam current or beam density incident upon the anode. This type of modulation fails when the time of transit of an electron from the cathode to the grid is comparable with the time required for the electrical impulse to reverse, i. e., with the period of reciprocal frequency.

In the Klystron other means are used for modulating the beam. In this latter case an electron beam originating from a cathode passes through two closely spaced grids, through a free space region of some extent known as the drift space, and subsequently through a second pair of closely spaced grids. The first pair of grids is known as

2

the buncher and the second pair is known as the catcher. The beam of electrons proceeding from the cathode is unmodulated, that is, it is purely a direct current beam. The incoming signal to be amplified or multiplied is applied between the grids of the first pair. Since the voltage of the incoming signal is in general much smaller than the velocity voltage of the electron beam, the beam is not brought to a stop at any time by this voltage. It does not, therefore, change the electron density in the beam since no electron is turned back in its flight. It does, however, change the velocity of the beam so that the electron passing the buncher pair of grids has a velocity which varies with time throughout the signal cycle.

Since these electrons leaving the buncher have velocities which vary in time, this procedure of modulation is known as velocity modulation. As the electron beam drifts through the empty space between the buncher and catcher, the faster electrons overtake the slower ones and by this process non-uniformities in the electron density are created so that at the time the beam reaches the buncher it has transformed its original velocity modulation into density modulation.

An equivalent of this phenomenon is visible in every-day life in the case, for instance, of racing cars on a narrow road. The racing cars cross the starting line in a long line at equal intervals. At the start they are spread out uniformly; however, due to their variations in speed they are eventually found in clusters. This is the phenomenon of bunching due to drifting.

This scheme of velocity modulation was resorted to as mentioned above to escape the limitation imposed by transit time upon the conventional tubes.

The present invention invokes a scheme of modulation which differs from both density and velocity modulation, namely, an electron beam is deflected. Such a deflection if properly utilized can accomplish similar effects and at the same time escape the limitations of transit time. In the technique of radio and radar utilized at the present time, the antennae from which the signals are eventually radiated are always separated from the electronic density in which the signals are generated. In the present invention the radiating antenna is made an integral part of the generating, amplifying or multiplying tube.

Accordingly an object of my invention is to provide a novel oscillation for ultra high frequencies.

A further object of my invention is to provide

a novel cathode ray tube ultra high frequency oscillation.

Still another object of my invention is to provide novel oscillation in which radiation is an integral part of the oscillation.

The details of the invention will become clearer with a perusal of the attached drawings in which:

Figure 1 is one version of the invention in which amplification or multiplication are involved; and

Figure 2 is another version of the invention in which the generation of self-sustained oscillations is involved.

In Figure 1 an electron gun 1 of the conventional type used in cathode ray tubes or in Klystrons is located within an evacuated space 2 surrounded by a glass envelope 3. From electron gun 1 there proceeds an electron beam 4 which passes between a pair of vertical deflecting plates 5. The deflected beam 6 then passes through hole 7 in a paraboloid metallic reflector 8 and impinges upon a vertical wire 9. This vertical wire 9 has a carefully chosen length and becomes the actual radiating antenna of the system.

To the center of wire 9 subsequently called the doublet is attached a lead wire 10 which passes through a vacuum seal 11 to a positive source of D. C. voltage. A lead wire 12 also connects metallic paraboloidal reflector 8 with a positive source of D. C. voltage through vacuum seal 13. The cathode of electron gun 1 is also connected by wire 14 through vacuum seal 15 to a negative source of direct current potential.

If now the direct current circuits of Figure 1 are energized, the electron beam would normally pass through the tube axially and impinge upon the center of doublet 9. If, however, voltages were impressed between the pair of deflector plates 5, the beam would be deflected either upward or downward and strike doublet 9 in some position other than its central point, or might miss doublet 9 entirely.

In Figure 1 deflector plates 5 are shown connected through radio frequency transformer 16 to an oscillator 17. If this oscillator delivers a radio frequency signal at some high frequency f , the resulting voltages of that frequency appearing upon deflector plates 5 will deflect the electron beam vertically with that frequency. Since the beam sprays electrons on to doublet 9 at various locations, the charges will therefore flow on doublet 9. Since any straight piece of wire has certain natural frequencies of oscillation, doublet 9 will tend to oscillate at its own natural frequencies.

As is well known, the natural frequencies of a straight piece of wire are such that the associated wave lengths bear a simple relationship to its length L . The lowest of these natural frequencies, the so-called gravest mode or fundamental frequency, is such that the associated wave length is almost exactly twice the length of the wire. Hence if the length of doublet 9 is L , the wave length of its fundamental frequency will be almost exactly $2L$. When excited by any means, doublet 9 will tend to oscillate at this frequency. These oscillations at the fundamental frequency will tend to damp themselves and die out unless the exciting stimulus is repetitive, re-exciting the fundamental periodically.

In order to excite this fundamental frequency, it is necessary that components of this frequency be present in the stimulus. This can be accomplished directly if the frequency f of oscillator 17 is precisely this fundamental frequency of di-

pole 9. In this case the relationship between the necessary frequency f of oscillator 17 and the length L of di-pole 9 would be given by the formula

$$f = \frac{c}{2L}$$

where c is the speed of light.

As an example, a length L of 5 centimeters might be chosen, in which case $2L$ is 10 centimeters. By the above formula the frequency f associated therewith is 3 billion, a familiar frequency amongst microwave engineers. In this case, doublet 9 would be excited directly from the frequency of deflection of the electron beam and would therefore oscillate continuously at this frequency. Under these circumstances, doublet 9 is an efficient radiator of electromagnetic waves and would normally radiate in all directions, but most strongly in its equatorial plane. Since it is usually desirable to confine the electromagnetic radiations into a narrow beam, the paraboloidal reflector 8 is used. Doublet 9 is then placed at the mathematical focal point of paraboloid 8.

By the focusing properties of paraboloidal surfaces which are well known in the field of optics, the energy radiated from a source located at the focal point will be reflected from the paraboloidal surface into a parallel beam of cross-section equal to the largest diameter of the paraboloidal reflector. This beam will have a small divergence angle and hence will concentrate the radiation into a very narrow cone as is desirable for most microwave radio and radar techniques.

Hole 7 in reflector 8 is necessary to provide access for the electron beam. This hole can be of a relatively small size compared with the extreme diameter of reflector 8 and hence will have a negligible effect upon the ray gathering efficiency of the reflector.

Such a device requires in this first version a source of alternating current of the same frequency as that to be radiated. Hence the difficulties of generating these frequencies has been laid upon the oscillator 17. It is, however, not necessary that oscillator 17 should deliver a frequency equal to the frequency which it is desired to radiate, namely that frequency which is related to the length L of doublet 9 by the formula given previously. It will suffice if the oscillator 17 delivers a frequency which is some sub-multiple of the desired frequency. In this latter case, the invention as shown in Figure 1 would be functioning as a frequency multiplication rather than merely as an amplifier as in the first-described version.

In order that doublet 9 may be excited at its fundamental frequency, even though the frequency of deflection of the electron beam is at a lower sub-multiple frequency, it is necessary to take measures to ensure that the stimulus impressed upon doublet 9 will contain components of its fundamental frequency. This can be accomplished by utilizing the phenomenon of distortion.

As is well known amongst electrical engineers, when a sinusoidal wave of a certain frequency is distorted into some non-sinusoidal shape, it is thereby caused to contain harmonics of the fundamental frequency, namely to contain frequency components which are multiples of the fundamental frequency. In the present invention, distortion can readily be achieved by causing the electron beam to sweep past the ends of

doublet 9. As a result of this, current would be impressed onto doublet 9 only over part of a cycle of the frequency of a deflection modulation of the electron beam, and therefore the impressed current upon doublet 9 would become highly non-sinusoidal.

As a result thereof, this impressed stimulus would contain frequencies which were multiples of the deflection frequency of the beam. Using a doublet of the same size as in the previous example, suppose that the frequency f of oscillator 17 were not 3 billion cycles, but rather $\frac{1}{3}$ of a billion cycles, i. e., 333 megacycles. Such a frequency is somewhat below the highest which can be obtained by the use of conventional vacuum tubes and can hence be generated in a more or less conventional manner by oscillator 17.

If this frequency were now impressed upon deflector plates 5 in such an amplitude as to sweep completely beyond the ends of doublet 9, the impressed stimulus into doublet 9 would contain amongst others a frequency nine times as great as the deflection frequency of the beam, i. e., it would contain a ninth harmonic. Since nine times this deflection frequency is precisely 3 billion cycles, i. e., 3000 megacycles, which is the natural fundamental frequency of doublet 9, doublet 9 would be continuously excited at this frequency and would hence carry out sustained oscillations at 3000 megacycles. Electromagnetic waves of the corresponding wave length, 10 centimeters, would therefore be radiated from doublet 9 and reflected from paraboloid 8 and transmitted in a narrow cone therefrom.

The version of the invention described in Figure 1 involved amplification or multiplication of an original impressed frequency. Another version of the invention portrayed in Figure 2 provides for the self-generation of the desired frequencies. Figure 2 is therefore a self-excited oscillator. In Figure 2, 21 is a conventional electron gun enclosed in an evacuated envelope 23. From electron gun 21 emanates an electron beam 24 which passes between a pair of deflector plates 25 and impinges upon doublet 29. To the center of the doublet is attached a lead wire 30 which passes through vacuum seal 31 to a positive source of D. C. potential.

From the cathode of electron gun 21 passes a lead wire 33 through vacuum seal 35 to a negative source of D. C. potential. To deflector plates 25 are attached two short straight pieces of wire 26 equal in length and having a carefully chosen length. The length of doublet 29 will again be called L and the distance between the extreme ends of the two wires 26 will be called L' . Doublet 29 will be referred to as the radiator, and the two pairs of wires 26 and associated deflector plates 25 will be referred to as the excitor. The spacing between the excitor 25, 26 and radiator 29 will be called d . The fundamental frequency of radiator 29 will again be related to its length by the same formula as given previously. Excitor 25, 26 will itself have a natural frequency. Its natural frequency will now be related to the length L' by the same simple formula as

$$f = \frac{c}{2L}$$

or radiator 29.

The fundamental frequency of excitor 25, 26 will depend not only upon the length L' but also upon the spacing and area of deflector plates 25. However, it has a fundamental frequency which can be adjusted by varying the length L' .

Suppose now that the direct current circuits of Figure 2 were energized. It would then be expected that the electron beam would pass axially from electron gun 21 through deflector plates 25 impinged upon the central point of radiator 29. Such a condition will prevail unless certain quantitative relationships exist. In case these quantitative relationships exist, this axial position of the electron beam will be unstable. To examine 10 into the nature of the conditions, which might cause instability of this position, it is necessary as in all stability questions, to inquire into the phenomenon subsequent to an arbitrary virtual displacement from equilibrium position. If namely the system returns to its original position after an arbitrary virtual displacement, the equilibrium is stable. If not, it is unstable. Suppose, therefore, that some disturbance deflects the electron beam 24 from the central portion of radiator 29. 15 In this case radiator 29 would be excited at its fundamental frequency and would emit electromagnetic waves in all directions.

These electromagnetic waves would impinge upon excitor 25, 26 and tend to set it into oscillation itself, particularly if the natural frequency of excitor 25, 26 were close to the frequency of the incident electromagnetic radiation. The degree of excitation therefore, of excitor 25, 26 due to the reception of electromagnetic radiation from 20 radiator 29 will depend upon the relationship between the lengths L and L' . Suppose that these two lengths have been so adjusted that the two natural frequencies are very near each other. In that case, excitor 25, 26 would itself be set into 25 vibration due to the reception of waves emanating from radiator 29.

The phase of the vibration set up in excitor 25, 26 will depend upon several factors, among 30 which is the distance d between the radiator 29 and excitor 25, 26. The oscillations set up in excitor 25, 26 by the receipt of radiation from radiator 29 will cause voltages to exist between the deflector plates 25, which voltages will of 35 themselves tend to deflect electron beam 24 and therefore to alter the point of impact of electron beam 24 on radiator 29, i. e., to influence the stimulus incident upon radiator 29.

Whether this influence tends to aid or to cancel the original arbitrary virtual stimulus depends 40 upon the phase relationship existing between this secondary and the primary stimulus. This phase relationship depends amongst other things upon the precise natural frequency of the excitor and upon the distance between the excitor and the 45 radiator d . It is therefore possible to adjust these perimeters so that this phase relationship is such that the secondary stimulus is in the proper direction to aid the primary virtual stimulus.

This entire scheme of creating instability is a 50 novel version of the conventional feedback used in all self-oscillating arrangements. Instability and hence self-sustained oscillations will be created if these perimeters are so adjusted that the feedback is in the proper phase and if in 55 addition the strength of the feedback is sufficient to overcome the dissipation and radiation losses of the system. The strength of this feedback will depend amongst other things upon the intensity of the electron beam 24. If this intensity is sufficient and if the spacing d is correct, and if the length L' of excitor 25, 26 bears the proper relationship to the length of radiator 29, then all the conditions for self-sustained oscillations will be met and the version of the inven- 60 65 70 75

tion portrayed in Figure 2 will generate self-sustained oscillations.

These oscillations will, however, be directly radiated into space from the radiator 29. This invention therefore is a source of electromagnetic radiation of extremely short wave length wherein radiation is accomplished directly without the necessity for circuits connecting the generator of the electrical oscillations with the antenna which radiates the waves. Both functions are carried out simultaneously by the invention as portrayed in Figure 2.

Referring again to Figure 1, the paraboloidal reflector 8 could at will be replaced by a reflecting array of parasitic antennae. Such parasitic arrays are now common in short wave techniques.

In both versions of the invention portrayed in Figures 1 and 2, it would be feasible to coat the end of the tube with a fluorescent coating which although functionally unnecessary, would assist in the alignment of the electron beam, since then it would be immediately possible to observe whether the electron beam was incident upon the radiating doublets or not.

This invention therefore utilizes a novel means of modulating an electron beam, namely the means of deflection modulation in contradistinction to density or velocity modulation, and also accomplishes direct radiation of electromagnetic waves without additional circuit arrangements.

Many modifications of the specific forms of my invention will now be obvious to those skilled in the art. Accordingly, I prefer to be bound not by the specific disclosures herein, but only by the appended claims.

I claim:

1. In an oscillator, an electron gun having an electron beam emitter, means for deflecting said beam, means including the elements of said gun for setting up ultra high frequency oscillations, 40 said means comprising a parabolic reflector and a vertical wire, and means for applying a positive charge to said reflector.

2. In an oscillator, an electron gun having an

electron beam emitter having a source of direct current potential applied thereto, means for deflecting said beam, means including the elements of said gun for setting up ultra high frequency oscillations, 5 said means comprising a reflector and a dipole of predetermined length, and means for applying a positive charge to said reflector.

3. In an oscillator, an electron gun having an electron beam emitter having a source of direct current potential applied thereto, means for deflecting said beam at a predetermined frequency, means including the elements of said gun for setting up ultra high frequency oscillations, 15 said means comprising a reflector and a dipole of predetermined length, and means for applying a positive charge to said reflector, whereby oscillations of the natural frequency of the length of the dipole are generated.

4. In an oscillator, an electron gun having an electron beam emitter having a source of direct current potential applied thereto, means for deflecting said beam at a predetermined frequency, means including the elements of said gun for setting up ultra high frequency oscillations, 20 said means comprising a reflector and a dipole of predetermined length, and means for applying a positive charge to said reflector, whereby oscillations of the natural frequency of the length of the dipole are generated and radiated.

EDWARD J. HEFELE.
